UNITED STATES PATENT OFFICE.

FRED C. LARGEN, OF CREIGHTON, NEBRASKA.

VENTILATOR.

1,383,469.

Specification of Letters Patent.

Patented July 5, 1921.

Application filed February 7, 1920. Serial No. 356,874.

To all whom it may concern:

Be it known that I, FRED C. LARGEN, a citizen of the United States, and a resident of Creighton, in the county of Knox and State of Nebraska, have invented new and useful Improvements in Ventilators, of which the following is a specification.

This invention relates to ventilators and refers more particularly to means for ventilating auditoriums, theaters, and the like places where large numbers of people may be congregated.

The primary object of this invention is the provision of means for securing a more efficient and thorough change of air in places in which a large number of people are congregated.

A further object of the invention is the provision of means for automatically directing an air current in any one of several elevations, as desired.

A still further object of the invention is to provide a ventilating system for auditoriums and the like which is associated with means controlled by the blower of the ventilator for introducing an air current in any one of several elevations.

A still further object of this invention is to provide a ventilating device whereby upon variations in speed of the blower the direction of air current is synchronously varied.

A still further object of the invention is to provide means associated and connected with a blower of the ventilator constituting a noise eliminating element.

Other objects and advantages of the invention will be apparent during the course of the following description taken in connection with the accompanying drawings.

In the drawings, forming a part of this specification and wherein like numerals are employed to designate like parts throughout the same,

45 Figure 1 is a side elevation of the device in operation,

Fig. 2 is a cross sectional view of the device,

50 Fig. 3 is a cross sectional view of the device taken on line 3—3 of Fig. 2,

Fig. 4 is a top plan view of a portion of the device showing the governing means associated therewith, and,

Fig. 5 is a view partly in section of the shutter control means.

55

In the drawings, wherein for the purpose of illustration is shown a preferred form of my invention, the numeral 1 designates the blower or fan casing which is formed of sheet metal, wood or any suitable material. 60 This casing 1 is provided in each side thereof with relatively large oppositely disposed openings 2 for the admission of air to the interior of the casing. The casing 1 is provided with an open end or air outlet 1' to 65 be hereinafter described. The casing is supported by upstanding support members 3 secured to a base 4 of suitable construction on which is also mounted a motor 5.

A revolute blower fan 6 is mounted 70 within casing 1, the driving shaft 7 of which is supported by journals 8 secured to cross bars 9 which extend across and are secured to uprights 3. As shown clearly in Fig. 3 the driving shaft 7 extends beyond the casing 1 and has mounted thereon at one end, a driving wheel 10 which is rotated by means of an endless belt 11 connected to the motor 5. Secured to the opposite end of shaft 7 75 is a governor 12 of ordinary construction. 80 The shaft 7 is provided exteriorly of the case 1 with collars 13 and 14 for the purpose of limiting the lateral movement of governor 12.

The fan or blower is of peculiar construction and as shown in Fig. 3 comprises two oppositely disposed substantially circular sides 15 each provided with a relatively large opening 15' which coincides in size with the openings 2 above mentioned and are disposed adjacent thereto. The sides 15 are connected by a plurality of blades 16 formed preferably of wood, sheet metal or other suitable material. As shown in Fig. 2 the plates 16 are tapered in thickness, having 90 the narrower edge toward the center and the thicker edge near the circumference of the blower, that is, the plates taper toward the center of the blower. These plates are secured against displacement by bolts or 95 screws (not shown) or by cleats 17 secured to the sides of the blower between which the plates are mounted. The blower is supported within the casing 1 by means of cross bars 18 secured to the sides of the blower 100 and at approximately right-angles with each

other, to which is secured a collar 19 which is also secured to driving shaft 7. Secured around opening 1' of the casing by any suitable means such as a band 20 is a flexible 5 air tube 21 formed of canvas, heavy cloth, or the like. The forward end of the flexible air tube 21 is secured to a cylindrical nozzle 22 by means of a band or other suitable securing means 23. The cylindrical nozzle 10 22 has communication with the air in the auditorium or theater to be ventilated. The cylindrical nozzle 22 is secured by means of a flange 22', to the side 34 (hereafter mentioned) of a compartment within which is 15 secured the entire device, the side 34 having an opening 34' communicating with cylindrical nozzle 22. Pivotaly mounted within cylindrical nozzle 22 are a plurality of shutters 24 which are connected by means of 20 rod 25 mounted exteriorly of the nozzle 22. As shown in Fig. 5 each shaft 26, supporting the shutters 24, is provided with an arm 27 which is secured to the above mentioned rod 25. 25 As shown in Fig. 4, one of the shutter supporting shafts 26 is extended for a short distance and has mounted thereon a depending lever arm 30. Secured to cross bar 9 is a bracket 28 on which is pivotally mounted 30 an angle arm 29. One portion of angle arm 29 is bifurcated at its end and is positioned around shaft 7 as shown at 31, the other extremity of arm 29 being connected to lever arm 30 by means of connecting rod 32. 35 As shown in Fig. 2 the shutters 24 lie with a very slight upward inclination when the blower fan is not in operation the various elements associated therewith being so connected. As shown in Fig. 1 the entire device 40 is positioned exteriorly of the auditorium proper, being positioned in a compartment having a roof 33 and the sides 34, one of which is provided with a plurality of shutters 35 for the admission of air to the compartments. It is obvious, however, that the 45 entire device may be arranged entirely separate from the auditorium or theater or at some distance therefrom according to the length of flexible air tube 21. 50 It is believed that the construction of the device will be readily understood from the accompanying drawings as above described and the primary object is to have the parts so positioned that upon an increase of speed 55 of the fan or blower there will be a corresponding increase in elevation of the shutters 24, thereby allowing a corresponding increase in elevation of the air current blown into the auditorium or the theater. It is 60 well known that in present day systems of ventilation the air current is usually blown at one elevation, no matter what the speed of the blower. This is injurious as well as very 65 uncomfortable to the assemblage of people in the auditorium. My device eliminates

this inconvenience by providing a synchronous elevation of the air current with the increase of speed of the blower.

It is to be understood that the form of my invention herewith shown and described is 70 to be taken as a preferred example of the same, and that various changes in the shape, size and arrangement of parts may be resorted to without departing from the spirit of the invention or the scope of the subjoined 75 claims.

Having thus described my invention, what I claim as new and desire to secure and protect by Letters Patent of the United States is:

1. A ventilator for auditoriums and the like comprising a casing, a fan rotatably mounted within the casing, means for rotating said fan, an air conduit connected to the casing, a plurality of shutters mounted in 80 said conduit, and means connected to the fan and to the shutters for obtaining changes in position of the shutters upon variations in the speed of rotation of the fan to deflect air at different elevations with respect to the 85 conduit.

2. A ventilator for auditoriums and the like comprising a casing, a rotatable fan mounted within the casing, a flexible air conduit secured to and communicating with the 90 casing and having an outlet, a plurality of shutters secured within said air conduit, and means connected to the fan and the shutters for obtaining changes in position of the shutters upon variations in speed of the fan 100 to deflect air passing from the conduit at an angle with respect to its outlet.

3. The combination with a casing and a blower mounted therein, of a plurality of pivoted shutters in the casing movable parallel to each other, and mechanism operated by the blower to move the shutters to an angular position with respect to the longitudinal axis of the casing to deflect the air at an angle with respect to the longitudinal 105 axis of the casing upon air forced from the casing above a predetermined velocity.

4. In combination with a ventilator for auditoriums and the like comprising a casing, a rotatable fan secured within the casing, an air conduit secured to and communicating with the casing and a plurality of shutters secured within said air conduit, means secured to the fan and to the shutters for obtaining a synchronous elevation of 110 the air current expelled from the air conduit upon an increase of speed of the fan.

5. A ventilator for auditoriums and the like comprising a casing, a fan provided with a plurality of blades rotatably mounted 115 in said casing, an air conduit secured to and communicating with the interior of the casing, a nozzle secured to the air conduit and communicating with the auditorium to be ventilated, a plurality of shutters secured 120 to the nozzle, and means connected to the fan and to the shutters for obtaining a synchronous elevation of the air current with the increase of speed of the fan.

within said nozzle, and means connected to the shutters and coöperating with the fan for obtaining synchronous changes in position of said shutters upon variations in speed of rotation of the fan to deflect the air expelled from the nozzle at an angle thereto.

6. The combination with a casing having an outlet and a rotatable blower mounted

therein, of a plurality of shutters pivoted in the casing to swing about horizontal axes 10 and operatively connected together, and mechanism for tilting the shutters upon change of speed of the blower whereby to deflect the air from the casing at different elevations.

FRED C. LARGEN.
